UNITED STATES PATENT OFFICE.

JOSEPH B. TATE, DELLIE L. WILHOIT, AND HARRY M. FOX, OF MARTINSVILLE,
ILLINOIS.

SANITARY DRINKING-FOUNTAIN.

1,249,244.

Specification of Letters Patent.

Patented Dec. 4, 1917.

Application filed May 23, 1916. Serial No. 99,430.

To all whom it may concern:

Be it known that we, JOSEPH B. TATE, DELLIE L. WILHOIT, and HARRY M. FOX, citizens of the United States, residing at Martinsville, in the county of Clark and State of Illinois, have invented new and useful Improvements in Sanitary Drinking-Fountains, of which the following is a specification.

10 This invention relates to sanitary drinking fountains and it consists in the novel features hereinafter described and claimed.

An object of the invention is to provide a fountain of the character indicated which is 15 of simple and durable structure and which is especially adapted to be used for elevating water from a well or other comparatively deep receptacle whereby the water is ejected at the top of the fountain in a relatively small stream or column and may be 20 used for drinking purposes.

With this object in view the fountain includes a standard adapted to be positioned at the top of the well or receptacle and having 25 a spring supported push rod slidably connected thereto.

A casing is adapted to be positioned in the bottom portion of the well or receptacle and a plunger is slidably mounted in the 30 said casing and connected with the said rod. Suitable check valves are located in the casing for controlling the flow of the water therethrough. The standard is provided at its upper end with a basin and a service 35 pipe extends from the casing through the standard and projects through the bottom of the basin. The said basin is provided with a suitable drain pipe.

In the accompanying drawing:—

40 Figure 1 is a side elevation of the fountain.

Fig. 2 is a detailed sectional view of the upper portion thereof.

Fig. 3 is a detailed sectional view of the 45 lower portion of the standard of the fountain and attached parts.

Fig. 4 is a detailed sectional view of a casing and associated parts used in the fountain.

50 The fountain includes a standard 1 which is provided at its upper end with a basin 2. The said standard and the basin may be of any suitable design or configuration and the standard is adapted to be positioned at the top of a well or other receptacle containing

the water. A drain pipe 3 connects at its upper end with the lower portion of the basin 2 and extends down along the intermediate portion of the said standard and terminates below the lower end thereof. 60

A casing 4 is located below the standard 1 and the said casing is provided at its top side with openings 5. A pipe 6 is connected with the top of the casing 5 and at its upper end the said pipe 6 connects with a cylinder 7 which in turn is connected at its upper end with the base of the standard 1. A rod 8 traverses the length of the pipe 6 and cylinder 7 and the said rod carries at its upper end a head 9 which projects 70 above the base of the standard 1. A coil spring 10 is housed in the cylinder 7. The lower end of the said spring 10 bears against the lower end of the said cylinder and the upper end thereof bears against the lower 75 end of the head 9. The spring 10 is under tension with a tendency to hold the rod 8 and head 9 in an elevated position. A plunger 11 is slidably mounted in the casing 4 and is connected with the lower end of 80 the rod 8. The casing 4 is provided at its lower end with a valve controlled port 12 and at its side with a valve chamber 13. A pipe 14 is connected at its lower end with the upper end of the valve chamber 13 and 85 the said pipe extends up and passes through the center of the standard 1 and the basin 2. The upper end of the pipe 14 is slightly above the upper surface of the said basin 2.

In operation the standard 1 is positioned 90 at the upper end of the well or receptacle and the casing 4 is positioned in the water contained within the said receptacle and in the vicinity of the bottom of the receptacle. When it is desired to use the fountain an operator depresses the upper end of the head 9 whereby the rod 8 is moved in a downward direction against the tension of the spring 10. As the rod 8 moves as above indicated the plunger 11 is moved in a 100 downward direction in the casing 4. Thus the air in the said casing is forced through the valve chamber 13 and pipe 14 out of the casing. When pressure is removed from the head 9 the said head and rod 8 are moved 105 in an upward direction under the tension of the springs 10 and as the plunger 11 moves away from the port 14 the water is drawn into the casing 4 through the said port and upon the next downward movement of the 110

plunger 11 the said water is forced through the valve chamber 13 and pipe 14 and out at the upper end thereof where it may be used for drinking purposes. Any water 5 that may fall into the basin 1 will drain from the same through the pipe 3 consequently the device cannot be rendered inactive by reason of the water freezing in the said basin.

10 From the above description taken in conjunction with the accompanying drawing it will be seen that a sanitary drinking fountain of simple and durable structure is provided and that the same may be easily and 15 conveniently used for elevating water which is not normally under pressure.

Having described the invention what is claimed is:—

A fountain comprising a standard, a cas-

ing located below the standard, a water pipe 20 connecting the casing with the standard, a plunger movably mounted in the casing, a pipe connected at one end with the casing, a cylinder connected at one end with the other end of said pipe, and at its other end with the standard, a rod movably mounted in the standard, cylinder and last mentioned pipe, and connected with the plunger, and a spring housed within the cylinder and bearing 25 at one end against the end of the second mentioned pipe and connected with the rod to hold the same in an elevated position.

In testimony whereof we affix our signatures.

JOSEPH B. TATE.
DELLIE L. WILHOIT.
HARRY M. FOX.
